UNITED STATES PATENT OFFICE.

AXEL L. LARSEN, OF ST. PAUL, MINNESOTA.

POISON-BOTTLE.

1,080,464.

Specification of Letters Patent.

Patented Dec. 2, 1913.

Application filed March 21, 1913. Serial No. 756,029.

To all whom it may concern:

Be it known that I, AXEL L. LARSEN, a citizen of the United States, residing at St. Paul, in the county of Ramsey and State of Minnesota, have invented new and useful Improvements in Poison-Bottles, of which the following is a specification.

This invention relates to poison bottles; and it has for its object the provision of an audible signal which can be arranged on the bottle, so as to be disturbed when the latter is handled and thereby cause a sounding of the alarm and indicate to the user that the bottle contains a poisonous or dangerous 15 drug.

Another object of the invention is the provision of an alarm attachment for poison bottles which may be readily connected with bottles of any standard construction.

With these and other objects in view, the invention consists of certain novel features of construction, combination and arrangement of parts, as will be hereinafter described and claimed.

In the accompanying drawings:—Figure 1 is a perspective view of the device, showing the application of the same to a bottle; Fig. 2 is a vertical section therethrough; and Fig. 3 is a perspective view of the device 30 detached from the bottle.

The device comprises an attaching member 1 which is preferably in the form of a flat resilient split band which may be made of a size with particular regard to the external diameter of a bottle neck, so as to accurately accommodate itself thereto and thereby properly sustain the alarm or sounding means in operative position.

The attaching device 1 is provided with an arm 2, which may be constructed of flat sheet metal bent upon itself at one end as at 3 so as to provide parallel connecting portions 4, between which the attaching member 1 may be engaged and soldered or otherwise secured in place in any suitable obvious manner. The arm 2 extends upwardly, as at 5, away from the attaching member 1 and it is terminally extended downwardly, as at 6, and riveted or otherwise suitably secured at 7 to a bell or similar sounding device or alarm means 8. The portion 9 of the

arm 2 at the point of connection of the portion 5 with the portion 6 is spaced from an adjacent portion of the bell 8 and arranged slightly within the hollow or cup of the bell 55 and as shown it is apertured at 10 for the reception of the upper end of a flexible and elastic tapper arm 11 which may be constructed of a single strip of rubber and provided at its lower end with a relatively 60 heavy metallic object 12.

Incident to the relative positions of the several parts of the device as described, it is evident that the bell 8 is normally sustained in a vertical position at one side of the bottle 65 neck and that the arm 11 is arranged normally in a perpendicular position with the metallic object 12 thereof spaced from the walls of the bell. This construction is such that when the bottle is disturbed in any way 70 or canted, the flexible arm 11 will be instantly influenced, and, as a consequence, the metallic object 12 thereof will be brought into sounding contact with the bell, so as to give the desired alarm and consequently indicate to the user that the bottle contains a 75 dangerous or poisonous drug or substance.

From the foregoing description, taken in connection with the accompanying drawings, the construction and operation of the invention will be readily understood without requiring a more extended explanation.

Various changes in the form, proportion and the minor details of construction may be resorted to without departing from the 85 principle or sacrificing any of the advantages of this invention, as claimed.

Having thus described my invention, what I claim is:—

An alarm for poison bottles comprising an 90 elastic attaching member, an arm secured to and extending from the attaching member, a bell secured to one terminal of the arm, a rubber element depending from the arm and located within the bell and a metallic sound- 95 ing object carried by said element.

In testimony whereof I affix my signature in presence of two witnesses.

AXEL L. LARSEN.
